AIRPLANE DOOR LOCK

Samuel Oxhandler, Flushing, N. Y., assignor to
 Sargent & Company, New Haven, Conn., a corporation of Connecticut

Application May 24, 1943, Serial No. 488,111

3 Claims. (Cl. 292—37)

This invention relates to door locks and more particularly to a lock for airplane doors for example, in that it provides a lock all parts of which are mounted within the plane of the outer surface of the door, that is, there are no projecting parts at the outer surface of the door either by way of operating handles or otherwise, which is desirable in installations for doors of airplanes.

As is well known, it is undesirable to have any projecting parts at the exterior of the body surface of an airplane and it is advantageous that all such surface be smooth and streamlined even to the provision of the fastening means for the various doors. It has been proposed in some instances to provide operating handles for the door bolts which are retractable or compressible so that when not in use they may be depressed into recesses provided, in order that they will lie in flush relation and not project from the surface of the door itself. In the present invention, this flush relationship of the door handles or bolt-operating members is achieved by arranging the outer bolt-operating handle in a recess or depression in the door itself and covering this depression with a small auxiliary door or closure member which may be locked in closed position so as to prevent access to the door handle by an unauthorized person. This auxiliary door is normally retained in closed position and is substantially flush with the surface of the main door but is so constructed that when not locked may be readily opened from the outside of the plane to provide access to the operating handle to open the door in case of accident, for example. The inner handle of the door is accessible at all times so that, regardless of whether or not the handle cover or auxiliary door is closed, the main door may always be opened from the inside.

One of the objects of the invention is to provide an airplane door lock no parts of which will project from the outer surface of the door.

A still further object of the invention is the provision of an airplane door lock having an operating member readily accessible from the inside of the door and having an outside operating member normally covered by a hinge plate which lies substantially flush with the outer surface of the door.

A still further object of the invention is the provision of an airplane door lock having an outer door handle disposed in a depressed position with respect to the outer surface of the door and a cover for the outer handle which cover lies substantially flush with the outer surface of the door.

Still another object of the invention is the provision of an airplane door lock of the type described, in which the outside operating handle is mounted in a depression within the surface of the door, which depression is covered by a cover plate which may be locked in a closed position substantially flush with the surface of the door and when not locked may be readily opened from the outside to permit access to the handle so that the door itself may be opened from the exterior of the plane.

To these and other ends, the invention consists, in the novel features and combination of parts to be hereinafter described and claimed.

In the accompanying drawings:

Fig. 1 is a front, elevational view of a door embodying my invention;

Fig. 2 is a view of the lock mechanism at the inside of the door;

Fig. 3 is a view of the lock mechanism at the outside of the door with the hinge cover for the outside handle being shown in open position;

Fig. 4 is a sectional view on a line 4—4 of Fig. 1;

Fig. 5 is a fragmentary view similar to Fig. 4 showing the cover in partially open position;

Fig. 6 is a sectional view on line 6—6 of Fig. 2;

Fig. 7 is an enlarged, detail, inside view of the locking means for the cover and a lever for opening the cover from the outside of the door; and

Fig. 8 is a sectional view on line 8—8 of Fig. 7.

To illustrate a preferred embodiment of my invention, I have shown in Fig. 1 of the drawings a door frame 10 which, for example, may be a part of an airplane, and a door 11 within the frame, this door being hinged at 12.

As shown, the door 11 is a part of a double door, the other unit of which is shown at 13, and the hinges 12 are mounted at the inside of the doors.

The door 11 may be locked in closed position by means of bolts 14 projectable into keeper openings 15 in the door frame. These bolts are mounted at the end of rods or links 16, the inner ends of which are pivoted as shown at 17 to a rotatable, bolt-operating disk 18, to which is secured the inner operating handle 19 as is clearly shown in Fig. 4.

It will be understood that the foregoing parts are mounted at the inside of the door, the handle 19 and operating disk 18 being rotatably carried by a cup-shaped supporting member 20 secured at the inside of the door by means of projecting ears 21 and bolts 22. The handle is provided with a hub member 23 carrying thereon a collar 24 rotatably mounted in a depressed por-

tion 25 of the outer wall of the cup-shaped member 20. Upon the inside of the cup-shaped member the outside handle 26 is secured to the hub member 23 which, as will be obvious, serves to hold the two handles in place in the mounting member 20 and connect them rotatably to this member.

An opening is provided through the door 11, opposite the mounting member 20, and a circular frame 27 is secured to the door in a position to surround this opening, this frame being so disposed that its outer surface is substantially flush with the outer surface of the door. With this construction, it will be seen from Fig. 4 for example that the outside handle 26 lies within the opening provided in the door and the cup-shaped mounting member 20 so that the outer surface of this handle does not extend outwardly beyond the outer surface of the door or beyond the outer surface of the frame member 27 which is substantially flush with the door. It will also be understood that the inside handle 19 is always accessible from the inside of the plane to operate the bolt disk 18 and thus withdraw or project the bolts 14, and that the outside handle 26 is accessible through the circular opening in the frame 27. Moreover, the opening in the door in which the outside handle 26 lies is of sufficient size to permit rotation of this handle and to permit anyone desiring to operate the door to insert his hand through the opening in the circular frame 27 and grasp and rotate the handle 26. Thus it will be seen that the bolts 14 may be operated from either face of the door.

Posts 28 are secured at the inner surface of the frame 27, the bolts 22 being threaded into these posts to secure the frame member 27 in place as well as securing the supporting member 20 to the door.

In order that the door may be locked when desired, against being opened from the outside, and also in order that all parts of the door be flush and smooth at the outside surface thereof, I provide a hinged cover for the opening in frame 27, which cover 30, as seen from Figs. 1 and 4, will be substantially flush with the frame 27 and therefore flush with the outer surface of the door. This cover is provided with U-shape hinge members 31 pivoted or hinged at 32 at the inside of the door, and around the pivot 32 is coiled a spring 33 which, in this instance, is tensioned to urge the cover 30 to its closed position shown in Fig. 4. This cover may be locked in this position by means of a key-operated lock 34 having a rollback 35 engageable in a notch or recess 36 provided in a post 37 secured at the inside of the cover at a point opposite the hinge edge thereof. By use of the proper key, the rollerback 35 may be rotated to engaging or non-engaging position when desired, and when in non-engaging position the cover 30 may be opened against the tension of the spring 33.

As the cover 30 is substantially flush with the outer surface of the door and fits closely in frame 27, and as it is desired to have no projecting parts on the cover or associated parts, it is necessary to have some means to assist in moving the cover to open position. The means provided herein is in the form of a push button 38 provided in a portion of the frame 27 as is the key-operated lock 34 and to the inner end of this push-button is pivoted a lever 39 also pivoted at its intermediate portion on a pivot 40 to the frame 27. The lever 39 has a hook-shaped end portion 41 designed to engage the inner surface of the cover

30 as shown in Figures 4 and 5 so that, when the push button is depressed as shown in Fig. 5 and the lever 39 rocked about its pivot 40, the end 41 of this lever will move the cover to partly-open position and enable an operator to grasp the edge of the same with his fingers to move it to fully-open position shown in Fig. 3 in which the outside handle 26 is accessible for operation.

In the case of the use of my device on airplane doors, it will be understood that the key-operated lock 34 will not normally be used when the plane is in operation as it is desirable to have the door side or the outside. As described above, the handle 19 is always accessible from the inside of the door. The handle 26 at the outside, however, will ordinarily be covered by the hinge cover 30 so that the outside surface of the door will be completely flush as is desired. If, however, it is necessary to open the door from the outside of the plane, accessibility to the handle 26 may readily be gained by depressing the push-button 38 which will serve to move the cover 30 from the position shown in Fig. 4 to that shown in Fig. 5, at which time it may be grasped and moved to fully open position shown in Fig. 3 to expose the handle 26 for operation. Thus, while there are no projecting parts on the outside of the door (the push button 38 and lock 34 also being flush with the outer surface of the door), the latter may be freely opened from within or without although the cover 30 will be held in closed position during operation of the plane.

If it is desired to lock the plane against entry from the outside, the lock 34 is operated to move the rollback 35 into engagement with the post 37 as shown in Figs. 7 and 8 which will lock the cover 30 closed and prevent access to the handle 26.

From the inside of the door, the latter is operated independently of the cover 30 as the handle 19 may be rotated when the cover is in closed position so that the structure providing for flush position of the parts from the outside of the door does not interfere with, or alter the operation of, the lock from the inside.

While I have shown and described a preferred embodiment of my invention, it will be understood that it is not to be limited to all of the details shown but is capable of modification and variation within the spirit of the invention and within the scope of the appended claims.

What I claim is:

1. In combination with a door having an opening therethrough, a cup-shaped mounting member secured at the inner surface of the door in a position to face said opening, a bolt-operating member rotatably mounted on the base of said mounting member, an inner handle secured to said operating member and having a hub projecting through the base of said mounting member, and an outer handle secured to the projecting end of said hub and lying within the space provided by said mounting member and by the opening through the door.

2. In combination with a door having an opening therethrough, a frame secured at the outer surface of the door about said opening, a mounting member at the inner surface of the door and secured to said frame, a bolt operating member rotatably mounted on said mounting member, an inner handle secured to said operating member and having a hub projecting through the mounting member, an outer handle secured to the projecting end of said hub and extending into the opening through the door, and a cover hinged to

said frame, which cover, when closed, lies substantially flush with the outer surface of the door.

3. In combination with a door having an opening therethrough, a frame secured at the outer surface of the door about said opening, a mounting member at the inner surface of the door and secured to said frame in spaced relation to the latter, a bolt operating member rotatably mounted on said mounting member, an inner handle

5 secured to said operating member and having a hub projecting through the mounting member, an outer handle secured to the projecting end of said hub and extending into the opening through the door to be disposed in the space between said frame and mounting member, and a cover hinged to said frame which cover, when closed, lies substantially flush with the outer surface of the door.

SAMUEL OXHANDLER.
